UNITED STATES PATENT OFFICE.

FRANZ X. WAGNER, OF NEW YORK, N. Y., ASSIGNOR TO UNDERWOOD TYPEWRITER COMPANY,
OF NEW YORK, N. Y., A CORPORATION OF NEW JERSEY.

TYPE-WRITING MACHINE.

No. 873,641.

Specification of Letters Patent.

Patented Dec. 10, 1907.

Original application filed November 12, 1904, Serial No. 232,413. Divided and this application filed May 18, 1905. Serial No. 260,983.

REISSUED

To all whom it may concern:

Be it known that I, FRANZ X. WAGNER, a citizen of the United States, resident of the borough of the Bronx, city, county, and State of New York, have invented certain new and useful Improvements in Type-Writing Machines, of which the following is a specification.

My invention relates to typewriting machines and has for its object to improve the carriage mechanism and the platen shifting mechanism of such machines.

My invention will be fully described hereinafter and the features of novelty pointed out in the appended claims.

The present application is a division of one filed by me in the United States Patent Office on November 12, 1904, Serial No. 232,413.

Reference is to be had to the accompanying drawings in which

Figure 1 is a central sectional elevation of a typewriting machine embodying my improvements; Fig. 2 is an elevation of such machine from the left side with the parts in section; Fig. 3 is a rear elevation partly in section; Fig. 4 is a sectional elevation substantially on the line 4—4 of Fig. 3; Fig. 5 is a sectional elevation of the lifting bar of the shifting frame; Fig. 6 is a detail elevation showing the spring for balancing the shift frame; Fig. 7 is a detail front view of the shift rail; and Fig. 8 is an enlarged section showing the connection of the shift rail with the shift frame.

The type bar action comprises the keys 1, mounted on levers 2, which are fulcrumed at 3, preferably in such a manner as to be easily removable. Each key lever is connected 40 with an elbow lever 4 by means of a pin and slot connection 5, said elbow lever being fulcrumed at 6 upon the frame of the machine. Each elbow lever is connected by means of a link 7, with a type bar 8, normally resting on 45 a cushion 9. The type bar 8 is fulcrumed at 10 upon the segment 11 and is preferably held in place by means of a latch 12. The key lever 2 also operates the escapement mechanism in any approved manner for instance, through the medium of a universal bar 13 engaged by a toe 2^a on the key lever 2. The carriage is fed in the usual manner by means of the spring 14, connected with the tape 15, one end of which is secured to the

carriage. The carriage consists of two portions, the front portion 16, which carries the platen 17, and the rear portion 18 which carries the feed rack 19 and may also carry other parts as for instance parts of the carriage stop mechanism which I have not shown in the present application but which have been embodied in another divisional application filed concurrently herewith. The feed rack 19 carried by the rear portion 18 of the carriage is adapted to be engaged by 65 a pinion A, carried by a shaft B near its upper end. Near its lower end the shaft B carries an escapement wheel C. A bar D extends from the center of the universal bar 13 and is secured at its rear end to a cross bar E 70 fulcrumed to the frame at F. The bar D carries an escapement pawl G, which normally arrests a tooth of the escapement wheel C on the shaft B. The bar D is further provided with a projection H in engagement 75 with the stop pawl I, fulcrumed on the frame of the machine at J and pulled against the projection H by a spring. Thus as the universal bar is moved rearward, the pawl G releases the escapement wheel C, and the end 80 of the stop pawl I is swung into the path of the escapement wheel. Both carriage portions are pivotally supported on the rear rod 20 of the machine frame, on which rod the carriage travels transversely of the machine. 85 The front portion of the carriage is also provided with one or more rollers 21 adapted to travel on a rail 22, carried by the shift frame 23.

As shown best in Figs. 7 and 8, the rail 22 90 is provided with pins 22^a adapted to be received in openings 23^a with sufficient play to allow the rail to swing pivotally relatively to the frame 23 and to remain substantially vertical even when the frame 23 is tilted 95 slightly backward by being raised to its upper position. This shift frame 23 is hung on the frame of the machine by means of knife edges 24 (see Figs. 2 and 6) and a spring 25 is employed to press the shift frame 23 upwards so as to counter-balance the weight of the front portion 16 of the carriage. In order that the action of the spring may be adjusted, I prefer to provide a series of notches, 23^a, in the shift frame as shown in 100 Fig. 6; by engaging the hook 25^a, connected with the spring 25, with one or the other of these notches, the purchase of the spring is 105

varied. The tension of the spring can be varied by engaging either the upper or the lower opening of the hook 25^a with the frame 23. The tension of the spring 25 may be further adjusted by means of the screw 25^b which holds the lower end of the spring. The mechanism for shifting the platen portion of the carriage into position for the printing of either small characters or capitals 10 is as follows: The shift frame 23 (see Figs. 2, 4 and 6) is connected pivotally at both ends by lugs 23^b with lifting bars 26, preferably made in two sections, adjustable by means of screws 26^a, so that the said lifting 15 bars may be lengthened or shortened. The upper portions of said bars have spring members 26^b carrying the connecting pins 26^c which enter into openings 26^d in the lifting bars 26; thus if it is desired to disconnect the lifting 20 bars 26 from the shift frame 23, to permit of the removal of said shift frame, the spring members 26^b are pressed away from the lugs 23^b, thus allowing the connecting pins 26^c to be withdrawn from the openings 26^d in the 25 lifting bars 26 and the shift frame to be removed. The lower end of each lifting bar has an opening through which projects a pin 27^a, mounted eccentrically upon a disk 27 secured to a shaft 28. This shaft is journaled 30 in the frame by means of ball bearings 29, and also carries a pinion 30 (see Figs. 4 and 5). This pinion is located only at one side of the machine and engages a toothed sector 31 on a rock shaft 32. This rock shaft at 35 the other end of the machine carries an arm 33 (see Fig. 1). Shift keys 34 and 35 respectively are adapted to engage the arm 33 and the arm of the sector 31. Thus by depressing either one of the shift keys the carriage 40 will be moved to its upper position, but if the shift key 34 has been depressed, the carriage will not return to its lower position upon the release of said shift key, but will be held in its upper position owing to the 45 engagement of a latch 36 pivoted at 37 with a projection 31^a of the sector 31. The latch 36 is under the influence of a spring 37^a and has a beveled surface 37^b at the bottom, which surface is adapted to be engaged by a 50 pin 35^a on the shift key 35. Thus if the carriage is locked in its upper position and it is desired to release it, the shift key 35 is depressed and the pin 35^a will swing the latch 36 clear of the projection 31^a and allow the 55 carriage to drop. It will of course be understood that if the shift key 35 is depressed while the carriage is in its lower position, the carriage will be raised but will drop back as soon as the shift key is released, owing to the 60 fact that the pin 35^a keeps the latch 36 away from the pin 31^a, until the latter is about in the position shown in Fig. 4. The latch 36 can be rendered inactive, if desired, by swinging 65 its upper end forward into frictional engagement with a surface of the frame, so that

the latch will be held out of the path of the shift key 35 until the operator restores the latch to its normal position.

I desire to call particular attention to the fact that the eccentric pins 27^a reach their dead center positions when the carriage is in its upper or its lower printing position, thus locking the shift frame 23 against accidental movement in either printing position.

In order to allow the carriage to be readily removed, I provide the following construction, shown in Fig. 3. The frame rod 20 on which the carriage moves has at its ends two recesses 20^a, facing in the same direction in which recesses are located pins 20^b, adapted to be engaged by stationary slotted supports 38 carried by the frame of the machine. The slots or recesses 20^a are somewhat wider than the supports 38 so that the rod can be slid lengthwise to disengage the pins 20^b from the slots of the supports 38. In order to lock the rod 20 in position, I provide a latch 39 movable vertically to fill the space between one of the supports 38 and the wall of the recesses 20^a as shown at the right in Fig. 90 3. By this construction the carriage can be readily removed from the machine, and another carriage of different width substituted therefor.

Various modifications may be made without departing from the nature of my invention.

I claim as my invention

1. In a typewriter, or like machine, a carriage, a shift frame for moving the carriage into different printing positions, bars connected with said frame, a pinion, a toothed sector engaging said pinion, a shaft carrying said pinion and provided with eccentric portions engaging said shift bars, and a shift key for swinging said sector.

2. In a typewriter, or like machine, a shift frame for the platen portion of the carriage, a shaft carrying two arms, one of which is provided with a toothed sector, means operated by said toothed sector for shifting the platen section of the carriage, a latch adapted to hold one of said arms in its raised position, and shift keys arranged to engage the said arms, one of the shift keys being constructed to swing said latch out of its locking position.

3. In a typewriter, or like machine, a shift key, a rocking arm adapted to be operated by said shift key and provided with a toothed sector lying in the same plane with the arms, a pinion engaging with said sector, and a shift frame for the platen section of the carriage, adapted to be moved by the turning of said pinion.

4. In a typewriter, or like machine, a removable carriage having a bar provided with recesses, stationary supports arranged to extend into part of said recesses, a pin and slot connection between said supports and said

- bar, and a latch extending into one of said recesses to lock the carriage to the frame of the machine.
5. In a typewriter, or like machine, stationary supports having open slots facing in the same direction, a removable carriage provided with a bar having recesses of greater width than said supports, and pins to fit into the slots of the supports, and a movable latch arranged to extend into one of said recesses between one of the supports and a wall of said recess.
6. In a typewriter, or like machine, a carriage having a front section carrying a platen and a separate rear section connected with said front section and carrying a member of the step by step feed mechanism, each section being mounted to swing about the same axis.
- 20 7. In a typewriter, or like machine, a carriage having a platen section and a separate escapement section connected therewith, each mounted to swing about the same axis.
8. In a typewriter, or like machine, a shift frame for the platen portion of the carriage, and a shift rail engaged by the carriage and loosely mounted on the shift frame to always remain substantially vertical.
- 30 9. In a typewriter, or like machine, a vertically movable shift frame for the platen portion of the carriage, and a shift rail engaged by the carriage and pivoted to said shift frame about a horizontal axis.
10. In a typewriter or like machine, a vertically movable shift frame for the platen portion of the carriage, said shift frame being pivotally supported by means of knife edges.
- 40 11. In a typewriter or like machine, a carriage, a shift frame for moving the carriage into different printing positions, and mechanism for operating said shift frame, said mechanism being upon a dead center when the carriage is in a printing position, to lock the shift frame against accidental movement.
- 45 12. In a typewriter or like machine, a carriage, a shift frame for moving the carriage into different printing positions, bars connected with said frame, eccentrics for operating said bars, and means for turning the eccentrics, said eccentrics being arranged to reach their dead center positions when the carriage is in a printing position.
13. In a typewriter or like machine, a carriage having a movable platen portion, means arranged to shift said platen portion and to move in unison therewith, a projection on said means, a latch normally in the path of said projection adapted to lock the platen portion of the carriage in one of its positions, and a shift key disconnected from the latch but arranged to disengage said latch from said projection. 55
14. In a typewriter or like machine, a carriage, a shift frame for moving the carriage into different printing positions, lifting bars detachably connected with said frame, eccentrics for operating said bars, and means for turning the eccentrics, said eccentrics being arranged to reach their dead center positions when the carriage is in a printing position. 60 70
15. In a typewriter or like machine, a carriage, a shift frame for moving the carriage into different printing positions, lifting bars connected with said frame, movable means mounted on said lifting bars for normally locking said shift frame and lifting bars together and arranged to be moved to permit said shift frame to be disengaged from said lifting bars, and mechanism for operating said lifting bars, said mechanism being upon 75 a dead center when the carriage is in a printing position, to lock the lifting bars against accidental movement.
16. In a typewriter or like machine, a carriage, a shift frame for moving the carriage into different printing positions, lugs on said shift frame, lifting bars connected with said lugs, spring pressed means mounted on said lifting bars for normally locking said lifting bars to said lugs, and adapted to be pressed 80 aside to permit said lifting bars to be disconnected from said lugs, and mechanism for operating said lifting bars, said mechanism being upon a dead center when the carriage is in a printing position, to lock the lifting 85 90 bars against accidental movement. 95

In testimony whereof, I have hereunto set my hand in the presence of two subscribing witnesses.

FRANZ X. WAGNER.
